(57) **CLAIM**

The ornamental design for a protective cover for a steering wheel, as shown and described.

DESCRIPTION

FIG. 1 is an upper perspective view of the protective cover for a steering wheel showing my design.

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is another perspective view thereof, showing installation on a steering wheel in broken lines; and,

FIG. 9 is a perspective view thereof, showing a flipped open position of a front panel to display surface decoration in broken lines.

The broken line features are presented for illustrative purposes and form no part of the claimed design.
